UNITED STATES PATENT OFFICE.

GUSTAV A. FRIESS, OF CHICAGO, ILLINOIS.

SHEET-GRIPPING MECHANISM FOR PRINTING-PRESSES.

1,284,086.

Specification of Letters Patent.

Patented Nov. 5, 1918.

Application filed November 23, 1916. Serial No. 133,046.

To all whom it may concern:

Be it known that I, GUSTAV A. FRIESS, subject of the Emperor of Germany, residing at Chicago, in the county of Cook and 5 State of Illinois, have invented certain new and useful Improvements in Sheet-Gripping Mechanism for Printing-Presses; and I do hereby declare the following to be a full, clear, and exact description of the invention, such as will enable others skilled in 10 the art to which it appertains to make and use the same.

This invention relates to improvements in sheet-gripping mechanism for printing 15 presses, and has for its particular object to provide mechanism of this character which is very simple and efficient.

The object of the present invention is to provide sheet-gripping mechanism which 20 includes means for gripping the sheet at points externally of the surface of the sheet-carrier, such as the cylinder of a press, and which thereafter moves the sheet, thus gripped, inwardly to lie upon the surface of such carrier, and which thereafter releases the sheet at a point exteriorly of such carrier, thus positioning the sheet to be more 25 easily gripped or engaged by other mechanism of the press for delivery to other points and, furthermore, prevents the holding 30 of the sheet upon the carrier-surface by air pressure.

The particular object of the present invention is to provide sheet-gripping mechanism 35 of the character defined which will operate smoothly and relatively noiselessly, as opposed to sudden and jerky motion involving the loud "clicking" of sheet-gripping mechanism now generally employed, it being desirable to reduce noise in the press-room in order that press-troubles may be 40 more easily detected and avoided.

A further particular object of the invention is to provide sheet-gripping mechanism 45 of the character defined in which the engagement and release of the sheets is effected by purely mechanical means acting independently of springs employed for maintaining the sheets firmly engaged.

50 The invention consists in the features of construction and combinations of parts hereinafter fully described and particularly claimed.

In the accompanying drawings illustrating a suitable embodiment of the invention:

Figure —1— is a fragmentary detail view

in side elevation partly in section, showing a press-cylinder equipped with sheet-gripping mechanism constructed in accordance with my invention.

60

Fig. —2— is a view similar to Fig. —1—, certain parts shown in Fig. —1— being omitted to expose the sheet-gripping mechanism to view, and showing the latter in another position.

65

Fig. —3— is a fragmentary detail section longitudinally of the cylinder on the line 3—3 of Fig. —1—.

65

Figs. —4—, —5— and —6— are fragmentary detail transverse sections on the 70 line 4—4 of Fig. —3— showing the gripping mechanism in its several positions.

75

My present invention relates more particularly to specific improvements upon the structure disclosed in my copending application Ser. No. 77839 filed Feb. 12, 1916.

75

Referring now to said drawings, 1 indicates the sheet carrier which, in the present instance, consists of a rotatable cylinder. In the ends of this cylinder are recesses 2 80 in which radially reciprocable plungers 3 are mounted. Each of said plungers is engaged by a helical compression spring 4 which normally holds the same against the stop 5 provided therefor. The plungers 3 85 at opposite ends of the cylinder 1 are connected by means of an anvil member 6 upon which the free ends of the gripper fingers 7 are adapted to bear for clamping a sheet between the latter and said anvil member 6. 90 The anvil member 6 constitutes a yoke which connects the plungers.

90

Journalized in openings in the plungers 3 is a rock-shaft 8 extending longitudinally of the cylinder 1 in the longitudinal groove 95 therein communicating at its end with the said recesses 2. The said shaft 8 is equipped at opposite ends with spur-pinions 9 rigid therewith and meshing with rack-bars 10. Each of the latter is provided at its inner 100 end with a plunger-head 11 reciprocably movable in guide-recesses 12 extending radially of the cylinder 1 and communicating with the inner ends of the recesses 2 therein. The said rack-bars 10 have a sliding engagement with the plungers relatively to which they are reciprocably movable and with which they are also adapted to be simultaneously moved. Each of the plungers 3 is provided in its outer side face with a guide-groove receiving the outer end portion of the rack-bar 10, the latter being held in 105

110

place therein by means of the plate 13 secured to the outer side face of each of said plungers 3. Mounted upon studs projecting from the outer faces of the plungers 3 are 5 antifriction rollers 14 which are adapted to engage the cam surfaces 15 carried by the rigid portion 16 of the frame of the press contiguous to the ends of the cylinder 1 and including a surface portion 17 concentric 10 with the axis of the cylinder 1 and substantially straight surfaces connecting at opposite ends with said concentric surface 17, said straight surfaces being adapted, when engaged by the rollers 14, to move the plungers 3 radially inwardly to the inner limit of their movement against the action of the 15 springs 4, said concentric portion 17 being adapted to maintain said plungers at said inner limit during the arc of movement coincident with that described by said surface 20 17, the other straight surface of said cam 15 being adapted to permit a gradual radial outward movement of said plungers.

The frame of the machine includes a 25 pending flange 18 rigid with the cam portion or member 15 and disposed outwardly of and parallel with the latter. Secured to the lower end portion of said member 18 are two cam members 19 and 20 respectively, 30 each provided with parallel inwardly projecting flanges 21 and 22 having divergent end-surfaces preferably rounded. The member 19 is disposed at one side of the vertical plane of the axis of the cylinder 1 and at a greater distance from the axis of 35 rotation than the member 20 disposed on the other side of said vertical plane of said axis, the opposing surfaces of the flanges 21 and 22 being disposed so that the ends 40 nearest the vertical plane in the case of the member 19 are disposed nearer the axis of rotation than the other ends of the flanges of said member and vice versa, the ends of the flanges of the member 20 disposed near- 45 est the vertical plane of the axis are disposed nearer the axis of rotation of said cylinder than the outer ends of said flanges.

Rigid with the plunger-heads 11 of the 50 rack-bars 10 are studs 23 carrying anti-friction rollers 24 which are adapted to pass between the flanges 21 and 22 of the respective members 19 and 20 successively to impart reciprocal motion to the rack-bar 10 independently of the reciprocal motion imparted to the plungers 3 by engagement of the rollers 14 with the cams 15. The gripper-fingers 7 are carried by the said shaft 8 and are adapted to swing through an arc of substantially one hundred degrees, more or 55 less, from their normal open position indicated in Fig. —4— to their normal closed position indicated in Fig. —5—. As the anti-friction rollers 24 pass between the flanges 21 and 22 of the member 19 the said 60 65 rack-bars 10 will be moved radially in-

wardly of the cylinder 1 thereby effecting rotation of the shaft 8 in the direction to cause the free end portions of the gripper-fingers 7 to engage the outer face of the anvil member 6. This closure is obviously 70 effected, as will be apparent from Fig. —1—, about simultaneously with the engagement of the cam 15 by the roller 14 so that, after said gripper fingers have engaged the edge portions of the sheet to be passed between 75 the cylinders 1 and 25, the anvil member 6 will, together with the gripper fingers, and without varying the position of the latter, move radially inwardly of the cylinder 1 to properly position the sheet upon the latter, 80 preferably with said edge portion and the engaging end portions of the gripper fingers disposed inwardly of the surface of said cylinder 1, thus preventing any contact of projecting metal portions with the surface 85 of the cylinder 25. As soon as the anti-friction rollers 14 have passed the concentric cam-surfaces 17 the plungers 3 will begin their outward movement, and this will be gradually accomplished so that the anvil 90 members attain the outer limits of their movement at a point in the rotation of the cylinder 1 which will keep said anvil members free of contact with the surface of the cylinder 25. At about the time that the 95 anvil member has completed its outward movement to the position shown in Fig. —6—, the anti-friction rollers 24 will enter between the flanges 21 and 22 of the member 20, and at this time a radial outward movement will be imparted to the rack-bar 10 which will serve to effect an opening of the gripper fingers 7 to release the sheet; said gripper-fingers then passing entirely out of the path of the sheet and out of the path 100 105 of any mechanism which may be provided on the press for engaging the now released edge-portion of said sheet.

Mounted on the shaft 8, contiguous to the ends thereof are two radial arms 26 having 110 bifurcated outer ends. In the latter there are pivoted two plungers 27. Mounted on a longitudinal wall of the recess or groove 2 are bifurcated members 28 in which heads 29 are pivotally mounted. Disposed between the latter and the heads of the plungers 27 are helical compression springs 30 which are held in place by the shanks of the plunger 27 and heads 29 respectively, in a 115 well-known manner.

As the gripper fingers 7 turn to their respective positions, the arms 26 compress the springs 30 but after said arms have passed that position in which the axes of the shaft 8 and the pivots of the plunger-heads 27 and heads 29 are in alinement with each other, said springs 30 will exert force tending to turn and hold the said gripper fingers in the respective positions indicated.

The action of said springs is, however, free 130

only when the rollers 24 are out of engagement with the respective pairs of flanges of the members 19 and 20 and thus serve only to exert pressure to hold said fingers 7 firmly down on the anvil member 6, and to hold the arms 26 engaged with the stops 31, respectively, in the intervals between the engagement of said rollers 24 with the flanges of said members 19 and 20.

10 The invention is very simple and efficient and operates very smoothly and with great accuracy, thus aiding in effecting a proper register of sheets to be printed in passing through the press.

15 While I have shown the preferred embodiment of my invention in the accompanying drawings, it will be obvious that the same is capable of modification and variation to adapt the same to various purposes 20 as mechanical skill and judgment may dictate without departing from the invention as defined in the appended claims.

I claim as my invention:

1. In a printing press, a sheet-carrying element provided in its face with a longitudinal groove terminating at its ends in inwardly extending guide recesses, an anvil-member disposed within said groove, a pair of plungers rigid with said anvil member disposed in said recesses, springs for normally maintaining said plungers and anvil at the outer limit of their movement, cams on the press-frame for moving the same inwardly against the action of said springs, a shaft journaled at its ends in said plungers and extending through said groove, gripper fingers carried thereby adapted to coact with said anvil member to engage sheets, reciprocable rack-bars mounted on and movable independently of said plungers, spur-pinions on said shaft meshing with said rack-bars and adapted to be rotated as the latter are reciprocated for actuating said fingers for engaging and releasing sheets, and coacting means on said rack-bars and the press-frame for imparting reciprocal motion to said rack-bars at intervals in respectively opposite directions.

2. In a printing press, a sheet-carrying element provided in its face with a longitudinal groove terminating at its ends in inwardly extending guide recesses, an anvil-member disposed within said groove, a pair of plungers rigid with said anvil member disposed in said recesses, springs for normally maintaining said plungers and anvil at the outer limit of their movement, cams on the press-frame for moving the same inwardly against the action of said springs, a shaft journaled at its ends in said plungers and extending through said groove, gripper fingers carried thereby adapted to coact with said anvil member to engage

sheets, reciprocable elements operatively connected with said shaft for rocking the same independently of the movements of said plungers, and coacting means on said rack-bars and the press-frame for imparting reciprocal motion to said rack-bars at intervals in respectively opposite directions.

3. In a printing press, a sheet-carrying element provided in its face with a longitudinal groove terminating at its ends in inwardly extending guide recesses, an anvil-member disposed within said groove, a pair of plungers rigid with said anvil member disposed in said recesses, springs for normally maintaining said plungers and anvil at the outer limit of their movement, cams on the press-frame for moving the same inwardly against the action of said springs, a shaft journaled at its ends in said plungers and extending through said groove, gripper fingers carried thereby adapted to coact with said anvil member to engage sheets, reciprocable rack-bars mounted on and movable independently of said plungers, spur-pinions on said shaft meshing with said rack-bars and adapted to be rotated as the latter are reciprocated for actuating said fingers for engaging and releasing sheets, and coacting means on said rack-bars and the press-frame for imparting reciprocal motion to said rack-bars at intervals preceding and following respectively, the reciprocal movements of said plungers.

4. In a printing press, a sheet-carrying element provided in its face with a longitudinal groove terminating at its ends in inwardly extending guide recesses, an anvil-member disposed within said groove, a pair of plungers rigid with said anvil member disposed in said recesses, springs for normally maintaining said plungers and anvil at the outer limit of their movement, cams on the press-frame for moving the same inwardly against the action of said springs, a shaft journaled at its ends in said plungers and extending through said groove, gripper fingers carried thereby adapted to coact with said anvil member to engage sheets, reciprocable elements operatively connected with said shaft for rocking the same independently of the movements of said plungers, and coacting means on said rack-bars and the press frame for imparting reciprocal motion to said rack-bars at intervals preceding and following respectively, the reciprocal movements of said plungers.

In testimony whereof I have signed my name in presence of two subscribing witnesses.

GUSTAV A. FRIESS.
